I
NVENTOR
James E. Gunter
By Thomas W. Clark
ATTORNEY

UNITED STATES PATENT OFFICE

JAMES E. GUNTER, OF BALTIMORE, MARYLAND

CONTAINER

Application filed March 17, 1927. Serial No. 175,965.

My invention relates to new and useful improvements in closures for containers and more particularly to one in which the cap retaining means may be readily removed without destroying the further usefulness of the cap or the container.

An object of my invention is to provide a sealed container which may be economically manufactured, and which can be readily and easily opened without the use of any tool and a cap, which after the container is opened, may be satisfactorily used for closing the container while the contents are being used.

Another object of my invention is to make such a container in which the cap retaining member is compressible or pliable, at least on its outer surface, and in which one end of the member projects for engagement as a handle.

Another object of my invention is to make such a container in which the cap retaining member has a resilient, or spring like core to tend to hold the member on the container.

Another object of my invention is to make such a container in which the cap retaining member has a core which may be removed from the member, so that the retaining effectiveness of the member will be destroyed and the cap may be removed.

Another object of my invention is to so shape or prepare the container that the cap retaining member will be held in its proper position thereon.

Other objects and advantages will be apparent from the following description and the accompanying drawings forming a part hereof and in which:

Figure 1 is a front view of a container, cap and retaining member.

Figure 2 is a cross sectional view on line 2-2 of Figure 1 looking in the direction of the arrows.

Figure 3 is a cross sectional view of a modification of the container and cap shown

in Figures 1 and 2 and embodying my invention.

Similar numerals refer to similar parts throughout the several views.

The container 1 has an outwardly flaring mouth 2, shown in Figure 2 as also having a bead 3 for further strengthening the container.

Around the container mouth or opening is a cap retaining member 4 having a relatively compressible or pliable coating and a removable core 5 of some tensile strength. This member has a projecting portion 6 to serve as a handle to remove the member or to remove the core and thereby permit the coating to collapse and permit the removal of the cap.

The cap 7 has an outer wall bent down and partly around the retaining member as shown at 8. This wall and the bending tool 65 that bends it over the retaining member, slightly compress the member where it projects to form a handle, so that the handle does not weaken the seam or obstruct the bending tool. In Figure 3 this outer wall 70 has a strengthening bead 9 on it. Both bead 9 and wall 8 should have a little distance between them and bead 3 or flared mouth 2 to allow for clearance to permit the removal of the cap over the top of the container.

The cap 7 is preferably of the friction type as shown. Around the container body, at convenient intervals, are struck up projections 10 to hold the retaining member upon the container body prior to and during the application of the cap.

After the container cap has been applied, it may be removed by hand, by pulling down on the handle 8. This will either cause the expansion of the cap wall and the compression of the retaining member to allow it to slide through the restricted exit between the container and cap walls, or it will pull the core from the member which will thereupon be unsupported and will either collapse it.

self or will be readily collapsible when the cap is raised.

The retaining member may be of any desirable cross section, a few possible modifications being shown in my patent, number 1,622,236, dated March 22, 1927, and the outer covering may be of any suitable material, such as rubber, cloth, paper, soft metal, or any other material which has sufficient resistance to the compression and shearing pressures between the container and cap. The core likewise may vary in composition, though preferably it is metal; its only necessity being that it have sufficient tensile strength to be removed and also that it hold expanded its covering. Preferably the core has sufficient spring in it to hold the member on the container body prior to the application of the cap.

As many changes might be made in the above arrangements and as many variations might be made without departing from the scope of the invention, it is intended that all the features herein described or shown in the accompanying drawings, shall be interpreted as illustrative, and that the invention be limited only by the following claims.

I claim:

1. The combination with a container, of a cap having a wall forming with the wall of the container a space, an elongated cap retaining member in said space with one end projecting therefrom, said member having a removable core, and being adapted, upon the removal of said core, to collapse and release the cap.

2. In a container, a cap therefor, a groove with a restricted opening formed by the container wall and the edge of the cap, an elongated cap retaining member in said space, said member having a removable core and being adapted, upon the removal of said core, to collapse and release the cap.

3. In combination, an open end container portion, a cap thereon, said container portion and cap being provided with adjacent surfaces forming a space having a contracted exit extending peripherally around the top of the container, an elongated cap retaining member disposed in said space of greater width facing said contracted exit than the width of the contracted exit, one end of said member projecting from said space, and at its point of projection therefrom, being compressed by said adjacent surfaces.

4. In combination, an open end container portion, a cap thereon, said container portion and cap being provided with adjacent surfaces forming a space having a contracted exit, a core contained elongated cap retaining member disposed in said space of greater width facing said contracted exit than the width of the contracted exit, one end of said member projecting from said exit, the core of said member being adapted to be removed

from said member through said contracted exit.

5. In combination, a container, a cap thereon, a compressible elongated cap retaining member surrounding the outer wall of the mouth or opening of the container, and the edge of the cap forming a bead removed from the container wall and partially surrounding said member laterally and forcing the same into close and retaining contact with said container, said member having one end thereof projecting from said bead and being compressed at its point of projection therefrom.

6. A container seam comprising a container wall, an elongated compressible cap retaining member, and a removable and replaceable cap, said cap having an outwardly facing wall parallel to and engaging an inner substantially vertical wall of the container and having a down-turned wall contracted inwardly below an outer periphery of the retaining member leaving an opening between said down turned wall and the container wall, and said member having a projecting end and at its exit from said down-turned wall being compressed thereby.

7. The combination with a container of a cap having an inner substantially vertical outwardly facing wall parallel to and engaging an inner wall of the container, the cap also having an outer depending wall forming with the outer wall of the container a space opened peripherally around the top of the container, a cap retaining member around the container in said space, one end of said member projecting from said space and at its point of projection therefrom being compressed by said outer cap wall, the retaining member being engaged and held in place by the outer cap wall and in turn holding the cap upon the container.

8. The combination with a container of a cap having an inner outwardly facing wall parallel to and engaging an inner wall of the container, the cap also having an outer depending wall forming with the outer wall of the container a space, a cap retaining member around the container in said space, said member having a removable core and being adapted, upon the removal of said core, to collapse and release the cap.

9. In combination, a container, a cap thereon, a compressible elongated cap retaining member surrounding the outer wall of the mouth or opening of the container, and means on the container wall below said member to hold it up toward said mouth or opening, and the cap having a down-turned wall contracted inwardly below an outer periphery of said member leaving an opening between said down turned wall and the container wall, and said member having one end projecting from said cap wall and at its point of exit therefrom, being compressed by said cap wall.

10. In combination with a container, a cap having a wall forming with the wall of the container a space opened peripherally around the top of the container, an elongated compressible cap retaining member in said space with one end projecting therefrom, said member having a resilient core sprung to hold said member in place on said container, and said member, at its point of projection from said space, being compressed by said cap wall.
